(57) **CLAIM**

The ornamental design for a joint bracket as shown and described.

DESCRIPTION

FIG. 1 is a perspective view of the joint bracket showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an another perspective view thereof; and,

FIG. 9 is a perspective view showing the joint bracket in an environment of use.

The broken lines in the drawings are for the purpose of illustrating environmental structure that form no part of the claimed design.
